RATION.

RAIL-ANCHOR.

1,312,158.

Specification of Letters Patent. Patented Aug. 5, 1919.

Application filed October 18, 1917. Serial No. 197,186.

To all whom it may concern:

Be it known that we, EDWIN G. BUSSE and ALBIN P. RISSELER, citizens of the United States, residing at Chicago, in the county of Cook and State of Illinois, have invented certain new and useful Improvements in Rail-Anchors, of which we do declare the following to be a full, clear, and exact description, reference being had to the accompanying drawing, forming a part of this specification.

The present invention has relation to that class of devices commonly known as rail anchors which are designed to prevent the longitudinal creeping of railroad rails. The invention has for its object to provide an extremely simple, light, cheap and effective form of rail anchor that can be readily applied to the base of a railroad rail and when so applied will be securely retained against slipping thereon or becoming displaced therefrom. To this end, the invention consists in the novel features of construction herein-after described, illustrated in the accompanying drawing and particularly pointed out in the claims at the end of this specification.

Figure 1 is a plan view of a rail anchor embodying our invention, the rail to which said anchor is applied being indicated in dotted lines and a portion of one of the cross ties being shown in full lines. Fig. 2 is a view in vertical section on line 2—2 of Fig. 1. Fig. 3 is a plan view of a portion of a rail anchor showing a modified form of the invention. Fig. 4 is a plan view showing a further modification.

In the drawing, A designates a railroad rail and B denotes one of the cross ties of the track on which the rail is located. In its preferred embodiment, our improved rail anchor is formed from a piece of metal, preferably sheet steel, that is cut and bent to substantially the form herein illustrated and described. As shown, our rail anchor comprises a body member C adapted to extend beneath the base of the rail A, this body member being provided at its opposite ends with jaws or hooks to engage the base flanges α and α' of the rail A. Preferably, the flange receiving spaces c beneath the jaws c' and c^2 and at the opposite sides of the rail are so shaped that the jaws shall bear upon the upper inclined faces of the rail flanges,

as indicated in the drawing, and by preference, the jaws c' and c^2 are bent angularly with respect to the body portion C of the rail anchor, as clearly shown in the drawing.

In order to enable a more effective gripping of the jaws c' and c^2 with the base flanges of the rail, the body portion C of the anchor is slightly bent in longitudinal direction, as shown by the dotted lines C⁴ in Fig. 1 of the drawing, and when the anchor has been placed in engagement with the rail, the straining of the body portion C incident to the application of the anchor will cause the jaws c' and c^2 to more securely engage the base flanges with a spring or tension grip.

In the preferred form of our invention, the rail anchor is formed at one end with an abutment or tie-engaging member C' that extends downwardly and outwardly from the body portion C, the outer end portion 75 of this abutment being adapted to bear against the side of the cross tie B adjacent to which the rail anchor is placed. By preference, the abutment C' is extended outwardly away from the body portion C of 80 the anchor, as by so doing a longer and more effective leverage is provided for causing the jaws of the anchor to securely grip the base flanges of the rail. If desired, however, the abutment may be formed by bending inwardly its end portion as illustrated at C² in Fig. 3 of the drawing. The exact shape, dimension and arrangement of the abutment C' (or C²) may be varied and ordinarily the top of the abutment will terminate about the bottom line of the body member C of the anchor.

In order to more effectively hold the rail anchor in engagement with the base flanges of the rail A, we have provided one end, 95 which in Figs. 1 and 2 is shown as that adjacent the tie engaging abutment with a locking flange C³. As shown, this flange C³, before the rail anchor is secured in position upon the rail, extends at such an 100 angle with respect to the body portion C of the anchor that the flange will not engage the base flange of the rail when the anchor is first applied thereon, nor will this flange C³ interfere with the application of the 105 anchor to the rail. When, however, the anchor has been applied to the base of the rail as shown in the drawing, the flange C³

will be bent by a suitable instrument to the position shown by dotted lines in Fig. 1 of the drawing, in which position the end of the flange C³ will bear against the edge of 5 the base flange a' of the rail and will effectively serve to prevent any accidental loosening or disengagement of the anchor upon the rail. In practice, our improved anchor will be applied to the rail by slipping 10 the body portion beneath the base of the rail and lifting and thereafter horizontally turning or rotating the anchor to cause the hooks or jaws c' and c² of the anchor to engage the base flanges a and a' 15 of the rail, the body portion being strained, as the jaws are caused to tightly engage the flanges of the rail, until the body portion is straightened or approximately straightened, as indicated by full lines in 20 Fig. 1 of the drawing, thereby holding the jaws by a spring tension grip in engagement with the rail base flanges. The locking flange C³ will then be bent from the position shown by full lines to the position 25 shown by dotted lines in the drawing, the flange being thus caused to firmly bear against the outer edge of the base flange a' of the rail.

In rail anchors of the type in which the 30 jaws of the anchor engage the base flanges of the rail with a "shackle" action and in which there is provided an abutment depending at one end of the anchor and embedded in the ballast of the track, the tendency 35 of the rail to move or creep in the normal direction of traffic serves to tighten the grip of the anchor jaws upon the rail flanges; but when the rail contracts or moves slightly in the opposite direction (the tie 40 abutment being embedded in the ballast of the road), there is a tendency of the anchor to rock slightly about such abutment as a pivot and thus loosen the engagement of the jaw at the opposite end of the anchor 45 with the corresponding base flange of the rail. When, however, the rail anchor is equipped with our improved locking flange hereinbefore described, all danger of the loosening of the anchor is avoided, because 50 as the rail A moves in a direction opposite that shown by the arrow in Fig. 1, the locking flange C³ effectively serves to prevent the loosening or disengagement of the jaws 55 of the anchor from the base flanges of the rail; but the locking flange C³ will not interfere with the "shackle" action of the anchor when the rail tends to creep in the direction of the arrow Fig. 1, carrying with it the jaw c² of the anchor farthest from the abutment. That is to say, the jaws of the anchor 60 are applied to the base flanges of the rail and are forced into engagement therewith by rotation of the anchor in one direction and the locking flange, when bent into engagement with the adjacent base flange, pre-

vents rotation of the anchor in reverse direction and so securely holds it in position upon the rail.

In the modified form of the invention illustrated in Fig. 4, the locking flange C³ is formed at the end of the anchor farthest from the abutment, instead of adjacent the abutment as in the construction described. In this form of the invention, as already set forth, the locking flange C³ will normally 70 extend in such position, as shown by full lines, that it will not interfere with the application of the anchor to the rail but when the anchor has been applied to the rail as above described, the locking flange C³ will 75 be bent from the position shown by full lines to the position shown by dotted lines in Fig. 4 so as to effectively serve to prevent the loosening of the anchor.

It will be noticed in the several forms of 80 the invention illustrated in the accompanying drawings, that the locking flange C³ is carried by a portion of the body of the rail anchor that extends laterally to a distance 85 from the adjacent rail engaging flange, so that when the free end of the locking flange C³ is turned inwardly it will more effectively engage the edge of the base flange of 90 the rail and so avoid the accidental movement of the rail more effectively than would 95 be possible with a flange arranged in close proximity to the jaw and adapted to be forced against the upper face of the base flange of the rail.

We claim as our invention:—

100

1. A rail anchor comprising a body portion having jaws at its ends to engage the base flanges of the rail, the body portion of said anchor being formed with a bent portion which under straightening strain tends 105 to draw the jaws of the anchor toward each other.

2. A rail anchor provided with jaws at its ends to engage the base flanges of a rail, the body portion of said anchor being 110 formed of resilient metal and with a portion offset or bent in horizontal direction, whereby when the jaws of the anchor are applied to the rail, the straightening strain of said offset or bent portion of the body will increase the grip of said jaws upon the flanges of the rail.

3. A rail anchor comprising a body portion having at its opposite ends jaws to engage the base flanges of a rail and having 120 adjacent one of said jaws a part extending outwardly to a distance therefrom and provided with a vertically disposed, bendable flange having a free end adapted to be turned into engagement with and abut 125 against the edge of the adjacent rail flange.

4. A rail anchor formed of a sheet metal plate having at its opposite ends jaws to engage the base flanges of a rail, one end of said plate being bent forwardly from the 130

body of the anchor to form a tie-engaging abutment, said body having a bent portion extending outwardly from the adjacent jaw and provided with a vertically disposed, bendable locking flange adapted to be turned into engagement with the edge of the adjacent rail flange.

5. A rail anchor formed of sheet metal having at its opposite ends jaws to engage the base flanges of the rail and having adjacent one of said jaws a tie abutting member bent forwardly from the body of the anchor, and a locking flange bent oppositely from the jaw adjacent which it is located and adapted to be turned inwardly to en-

gage with the edge of the adjacent rail flange.

6. A rail anchor comprising a body in section having opposite end jaws adapted to be applied and forced into engagement with the base flanges of the rail by the rotation of the anchor in one direction, and said anchor having adjacent one of its jaws a part extending outwardly therefrom and provided with a vertically disposed, bendable flange adapted to be turned into engagement with the adjacent rail flange to lock the anchor against reverse rotation.
